UNITED STATES PATENT OFFICE.

JOHAN M. ANDERSEN, OF BOSTON, MASSACHUSETTS, ASSIGNOR TO ALBERT AND J. M. ANDERSON MANUFACTURING COMPANY, OF BOSTON, MASSACHUSETTS, A CORPORATION OF MAINE.

OIL TIME-SWITCH.

1,094,694.

Specification of Letters Patent. Patented Apr. 28, 1914.

Application filed July 23, 1908. Serial No. 444,978.

To all whom it may concern:

Be it known that I, JOHAN M. ANDERSEN, a citizen of the United States, residing in Boston, county of Suffolk, and State of Massachusetts, have invented an Improvement in Oil Time-Switches, of which the following description, in connection with the accompanying drawings, is a specification, like letters on the drawings representing like parts.

This invention relates to a time switch or circuit controlling apparatus of the class shown and described in U. S. Patent No. 779,249 granted to me January 3, 1905, and has for its object to improve the construction of the same and more particularly the circuit controlling portion thereof, whereby the time switch is especially adapted among other uses for controlling the circuits of high potential currents.

The invention further has for its object to provide a novel construction of apparatus as will be described, whereby the time operated switch may be located in a well containing oil or other fluid and which is attached to the time switch apparatus so as to form part thereof whereby an oil time switch may be supplied to the trade as a single compact structure.

These and other features of this invention will be pointed out in the claims at the end of this specification.

Figure 1 is a front elevation with the oil well in section of a time switch embodying this invention. Fig. 2, a like view with the door of the box containing the time movement removed. Fig. 3, a rear elevation and section of the apparatus shown in Fig. 1, with the switch open. Fig. 4, a side elevation and section of the apparatus shown in Fig. 3, looking toward the left. Fig. 5, a sectional detail on the line 5—5. Fig. 6, Figs. 6 and 7 are details to be referred to, and Figs. 8 and 9, details in plan to be referred to.

Referring to the drawings, *a* represents a metal box or case containing the clock mechanism or time train *b*; the selective mechanism operated thereby through the gear *c* and comprising the toothed disk or wheel *d* provided with radial slots *e* into which are extended fingers on the hands or levers *f*; and a motor mechanism for operating the movable member of a circuit controller as will be described.

The clock mechanism, the selective mecha-

nism and the motor mechanism are and may be substantially the same as shown and described in the patent referred to, except as to details as will be hereinafter described.

The motor comprises a spring *g* located in a barrel *h* provided with gears *i*, *j*, the gear *i* being operatively connected with the toothed disk *d* by gears *k*, *l*, *m*, and the gear *j* meshing with a gear *o* on a shaft *p*, which is extended through a partition wall 10 in the box or case *a* and has fast on it a disk 12 (see Fig. 3) provided with bosses 13, 14, between which extends a detent lever 15 loosely mounted on the shaft *p*. The disk 12 has eccentrically connected with it at 16, one end of a connecting rod 17 preferably made as herein-represented and comprising metal end pieces and an intermediate piece of insulating material, such as hard rubber, which is secured to the metal end pieces by screws 19, 20.

The detent lever 15 is provided at its opposite ends with two detents or arms 21, 22, with which coöperates a finger 23 on an escape lever 24 pivoted to the wall 10 and having a second finger or projection 26 with which coöperate tripping dogs 27, which are connected with the hands *f* of the selective device and are rotated with the toothed wheel or disk *d*, so that at predetermined times, the tripping dogs will be moved into engagement with the finger 26 and turn the escape lever on its pivot, so as to disengage the finger 23 from the detent arm 21 and permit the motor 10 to rotate the disk 12 until a finger 30 on the detent arm 22 (see Fig. 6) is brought into engagement with the finger 23 on the escape lever, for a purpose as will be described. The disk 12 is thus held from rotating under the influence of the motor, until the tripping dog 27 passes out of engagement with the finger 26 and permits a spring 31 to turn the escape lever, so as to move the finger 23 toward the disk 12 and into line with a recess or arch 310 in the detent arm 22, thereby allowing the motor 10 to move the disk 12 so as to complete a half revolution, or until the detent arm 21 on the other end of the lever 15 is brought into engagement with the finger 23 on the escape lever.

The blow of the detent arm 21 against the escape finger 26 is cushioned by a spring 33 acting on a button or plug 34 in a socket in the boss 13 on the disk 12. Provision is made for releasing the motor independently

of the time operated selective mechanism, and for this purpose I employ a crank 35 on a rock shaft 36, which is extended through the partition wall 10 to the front of the box, or case *a* and is provided with a finger piece or arm 37, see Fig. 2, by which the operator can rock said shaft so as to engage the crank 35 with a lug 38 on the escape lever and cause said crank to turn the escape lever so as to disengage the finger 23 from the detent arm 21, after which the operator releases the finger piece, and the spring 31 turns the escape lever so as to disengage the finger 23 from the detent arm 22 and allow the motor to rotate the disk 12 a half turn as above described.

The box or case *a* is secured to a supporting base plate or platform 40, provided as shown with upright brackets 41 having holes 42 for the reception of screws or bolts by which the apparatus may be secured to a suitable upright support, (not shown).

The motor mechanism within the box or case *a* is connected with the movable member of a circuit controller located below the base plate 40, by the connecting rod 17, which is extended through suitable coinciding slots 42, 43 in the bottom of the box or case *a* and in the base plate 40 (see dotted lines, Fig. 3). The movable member referred to, may be made as herein shown and consists of a pair of laminated spring brushes 44, which are secured as by screws 45 (see Fig. 4) to the underside of a carrier, shown as a bar or piece 46 of hard rubber or other insulating material, which is bodily movable on guide rods 47 depending from a block 48 of insulating material, which is screwed or otherwise fastened to the underside of the base plate 40. The block 48 has a hole through it for the passage of the connecting link 17. The contact members 44 are located near the opposite ends of the carrier 46 and coöperate with fixed contact members or terminal metal blocks or pieces 49, which are screwed or otherwise secured to a plate or slab 50 of slate or other suitable insulating material, which is suspended from the base plate 40 by corner bolts or rods 51 provided with sleeves or coverings 520 of insulating material.

The carrier 46 for the movable contacts is connected with a rocking device or lever 52 mounted to turn on a pivot pin or shaft 53 supported by a metal frame or casting comprising a horizontal portion 55 (see Figs. 4, 8 and 9), from one end of which are extended studs or posts 56, which are suitably fastened to the block 48 of insulating material, and from the other end of which extend lugs 57 (see Fig. 2) through which the pivot pin 53 is passed, and which are separated sufficiently to receive the rocking device or lever 52. The lugs 57 have extended from them ears 58 through which pass the

guide rods 47. The pivot pin or shaft 53 is extended through the guide rods 47 and is detachably secured thereto by cotter pins 59 or otherwise.

The rocking device or lever 52 is provided as shown with three arms 60, 61, 62 (see Fig. 4), the arm 60 being joined by a link 63 to a metal stud 164 secured to the carrier 46 near its center; the arm 61 being extended into a slot 64 in the lower end of the connecting rod 17, and the arm 62 being extended from the opposite side of the pivot and having attached to it a cross bar 65 forming a counter-weight for the movable member of the switch. The arm 61 is made narrower than the slot 64 and is preferably made rounding or curved on its upper and lower surfaces so as to conform to the curved end walls of the said slot. The arm 62 is provided with a projection 66, which co-operates with a projection 67 on the frame (see Figs. 1, 8 and 9), so as to form a stop for the switch in its closing movement.

Provision is made for interposing barriers of insulating material between the pairs of contacts, and for this purpose, a block or piece 70 of hard rubber or other insulating material is erected upon the slab or plate 50 between the pairs of stationary terminals or contacts 49 and is of a length substantially equal to the distance between the terminals of each pair of terminals. The movable carrier 46 has secured to its under side cross bars or pieces 72 of insulating material, arranged so as to be interposed between the insulating barrier 70 and the movable contact members 44. The block 70 and the bars or pieces 72 are made of a height substantially equal to the distance between the plate 50 and the carrier 46 in the closed position of the switch (see Fig. 2).

The switch mechanism is designed to be inclosed in a well or box 75, which contains oil or other fluid medium 76 for reducing the danger of opening and closing a switch in a circuit whose current is of high potential or tension, said box-or-well being open at its top and secured to the base plate 40 by means of rods 77 extended through the sides of the well and through lugs or ears 78 depending from the base plate 40, said rods being provided at their ends with retaining devices or nuts 79.

The stationary contacts or terminal members 49 are arranged in pairs as herein shown, and are adapted to be connected by the main contact brushes 44 and also by auxiliary contact members, shown as substantially T-shaped conducting pieces 80, which are vertically movable in guides 81 connected together by a metal bar 82 fastened to the carrier 46, said bars being interposed between said carrier and the main contact members or brushes 44. The auxiliary contact members 80 are adapted to engage

70

75

80

130

the stationary contact members or terminal pieces 49 and are yieldingly engaged therewith by the springs 84 attached to the carrier 46.

5 The stationary terminals 49 have secured to them metal rods or bars 85, which are extended up through the base plate 40 and into hollow insulators 86, extended above and below the base plate and firmly secured thereto by clamping bars 87, which are provided at their ends with holes or openings to permit said bars to be slipped over the portion of the hollow insulators above said base plate, after which said clamping bars 15 are fastened as by screws 90 (see Fig. 4) to the upper side of said base plate. The metal rods 85 below the hollow insulators are preferably provided with a covering or sleeve 91 of insulating material. The terminal rods 20 85 extended up into the hollow insulators have connected with them in any suitable manner insulated conductors 92.

In the present instance, the switch is shown as a double pole double break switch, 25 and in operation the switch is opened and closed at predetermined intervals, selected by moving the hands or levers *f* into engagement with the slots *e* in the toothed disk *d* corresponding to the times at which it is 30 desired to open and close the switch.

The motor *g* is released as above described, and first rotates the disk 12 sufficiently to engage the finger 23 with the detent arm 22, and thus enable the final release 35 of the motor to take place when the edge of the tripping dog 27 passes the edge of the escape finger 26.

In Figs. 1 and 3, the switch is shown in its open position, and the connecting rod 17 in 40 what may be termed its elevated position. At the selected time, the motor *g* is released and the disk 12 rotated in the direction of the arrow 94, Fig. 3, until the detent arm 22 engages the finger 23 of the escape 45 lever 15, after which the motor is fully released and moves the connecting rod 17 down until the disk 12 has made a half turn, at which time the movable contacts 44, 50 80 are engaged with the stationary contacts 5 or terminals 49 and the switch is closed as represented in Fig. 2.

When the crank or arm 61 is depressed as described, the counterweighted arm 62 is elevated, and the toggle formed by the 55 crank or arm 60 and link 63, is straightened. The switch remains closed until the motor is again released by the selective device, whereupon the connecting rod 17 is moved upward into the position shown in Fig. 3, and 60 on its upward movement said rod lifts the crank or arm 61 and rocks the lever or device 52 so as to move the toggle 60, 63 into its inclined position shown in Fig. 4 and so as to lower the counterweight 65, which balances or substantially balances the weight of

the movable member of the switch and its carrier, consequently relieving the motor *g* of an excessive load.

The oil well 75 may be filled through an opening 96 in the base plate 40, which is provided with a cover 97, to such level as to cover the movable contact members in their open position as represented in Fig. 4 and jumping of the arc from one switch or side of the switch to the other is effectively prevented by the arc interrupting walls or barriers 70, 72.

The box or case *a* containing the time mechanism is provided with a door 100 hinged thereto, and on its rear side, said box 80 is provided with a removable plate 101 (see Fig. 4). Provision is made for effecting a water and dust-tight joint between said door and plate and the box or case. To this end, strips 102 of rubber are interposed between 85 the back plate 101 and the walls of the opening in the back of the box or case, and strips 102 of rubber are fitted into channels or grooves at the top, bottom and sides of the door 100 on the inner side of the latter, and 90 said strips coöperate with an edge 103 on the top, bottom and side walls of the box or case *a* at the front thereof. The packing strips 102 are forced into air and dust-tight engagement with the edges 103 by slide bars 95 105 movable in a guideway formed by a plate or piece 107 (see Fig. 5) secured to a cross rib or raised portion 108 on the inner side of the door 100, said slide bars being connected by links 109 to diametrically opposite studs 110 on a disk 112 rotatable in a socket in the cross piece 108 and actuated by a handle 113 on the outside of the door. The front ends of the slide bars 105 are beveled (see Fig. 5) and coöperate with lugs 100 114 (see Fig. 2) on the inner surface of the side walls of the box or case *a*, so as to force the edges 103 into the rubber packing strips 102.

Claims:

1. In combination, a circuit controller provided with a movable member, a rocking device provided with an arm, a link pivoted at one end to said arm and at its other end to said movable member to form a toggle between the latter and said rocking device, a second arm on said rocking device, a counterweight for said movable member connected with said second arm, a third arm on said rocking device, and means coöperating with said third crank or arm for rocking said device to straighten the toggle and operate said movable member, substantially as described.

2. In combination, a circuit controller comprising a plurality of pairs of fixed members, and a plurality of movable members coöperating therewith, a carrier for said movable members, a stationary arc interrupting wall interposed between said stationary members, movable arc interrupting

walls attached to said carrier between said movable members and arranged with relation to said stationary wall to be interposed between said wall and the fixed contact members in the closed position of said circuit controller, substantially as described.

3. In combination, a circuit controller comprising a plurality of pairs of fixed members, and a plurality of movable members coöperating therewith, a carrier for said movable members, a stationary arc-interrupting wall interposed between said stationary members, movable arc-interrupting walls attached to said carrier between said movable members and arranged with relation to said stationary wall to be interposed between said wall and the fixed contact members in the closed position of said circuit controller, a rocking device, means to connect said carrier with said rocking device, and means to operate said rocking device, substantially as described.

4. In combination, a circuit controller comprising a plurality of pairs of fixed members, and a plurality of movable members coöperating therewith, a carrier for said movable members, a stationary arc-interrupting wall interposed between said stationary members, movable arc-interrupting walls attached to said carrier between said movable members and arranged with relation to said stationary wall to be interposed between said wall and the fixed contact members in the closed position of said circuit controller, a rocking device, means to connect said carrier with said rocking device, and means coöperating with said rocking device to move the same in opposite directions, substantially as described.

40 5. In combination, a circuit controller comprising a plurality of pairs of fixed members, and a plurality of movable members coöperating therewith, a carrier for said movable members, a stationary arc-interrupting wall interposed between said stationary members, movable arc-interrupting walls attached to said carrier between said movable members and arranged with relation to said stationary wall to be interposed between said wall and the fixed contact members in the closed position of said circuit controller, a lever provided with a plurality of arms, means to connect one of said arms with said carrier, a counterweight attached to another of said arms, and means coöperating with a third arm to turn the lever in opposite directions, substantially as described.

60 6. In combination, a circuit controller comprising a fixed member and a movable member, a rocking device provided with a plurality of arms extended in different directions, a link pivoted at its upper end to one

of said arms and at its lower end with the said movable member to form a toggle, a weight located on the opposite side of the pivot of said rocking device and connected with a second arm thereof, a link provided with a slot into which the third arm of said rocking device is extended, and means for reciprocating said link to rock the said device and effect movement of said movable member in opposite directions, substantially as described.

7. In combination, a circuit controller comprising a fixed member and a movable member, a rocking device provided with a plurality of arms extended in different directions, a link pivoted at one end to one of said arms and at its other end with the said movable member to form a toggle, a weight located on the opposite side of the pivot of said rocking device and connected with a second arm thereof, and means for rocking said device operatively connected with the third arm thereof, substantially as described.

8. In combination, a supporting frame, a circuit controller located below said supporting frame and provided with a movable member, an oil well suspended from said supporting frame and inclosing said movable member, a motor for said circuit controller located above said supporting frame, a box or case supported by said frame above the same and inclosing said motor, a link pivotally connected at its upper end with the motor within said case and extended through and below said supporting frame into said oil well and provided at its lower end with a slot, and a rocking device located below said supporting frame and operatively connected with the said movable member and provided with an arm extended into said slot, substantially as described.

9. In combination, a supporting frame, a circuit controller located below said supporting frame and provided with a movable member, an oil well suspended from said supporting frame and inclosing said movable member, a motor for said circuit controller located above said supporting frame, a link pivotally connected at its upper end with said motor and extended through and below said supporting frame and into said oil well, and a rocking device located below said supporting frame and operatively connected with said movable member and with said link, substantially as described.

In testimony whereof, I have signed my name to this specification in the presence of two subscribing witnesses.

JOHAN M. ANDERSEN.
